(57) **CLAIM**

The ornamental design for a lid for a beverage container holder, as shown and described.

DESCRIPTION

FIG. 1 is a perspective view of a lid for a beverage container holder showing my new design, the broken line showings of inner and outer containers being for the purpose of illustrating environmental structure forming no part of the claimed design;

FIG. 2 is a left side elevation view, the right side elevation view being a mirror image thereof;

FIG. 3 is a top plan view; and,

FIG. 4 is a bottom plan view.
